UNITED STATES PATENT OFFICE.

FREDERICK H. BELLMORE, OF NEW BEDFORD, MASSACHUSETTS.

VALVE-TAPPET.

1,401,234.

Specification of Letters Patent. Patented Dec. 27, 1921.

Application filed January 12, 1921. Serial No. 436,848.

To all whom it may concern:

Be it known that I, FREDERICK H. BELLMORE, a citizen of the United States, and a resident of New Bedford, in the county of 5 Bristol and State of Massachusetts, have invented certain new and useful Improvements in Valve-Tappets, of which the following is a specification.

My present invention relates generally to 10 valve tappets, and more particularly to that type of valve tappet which includes a cylindrical body having a lower annularly flanged cam engaging end and into whose upper slightly reduced end an adjusting screw 15 works and is controlled by a lock nut. This is substantially the type of tappet utilized in connection with detachable head motors and is open to practically but one objection and that is the noisy action of the parts 20 unless a very fine accurate adjustment of the adjusting screw is maintained at all times. This adjustment is usually effected with the parts cold or practically so by adjusting the nut with a piece of ordinary 25 paper between the same and the lower end of the valve stem which the tappet is adapted to actuate, so as to thus allow for natural expansion when the parts are heated in action, otherwise the valve would not be permitted to seat properly. 30

It is the object of my invention to provide means whereby to eliminate this noise with the slightest possible change in construction, and at the same time provide for more 35 thorough lubrication of the tappet without danger of overlubrication and waste of oil.

In carrying out my invention I provide a tappet whose construction so slightly differs from that of the ordinary tappet that with 40 its parts pressed together its external appearance is precisely the same as that of the usual tappet although my invention proposes its manufacture in two parts instead of the usual single part and provides for 45 a coaction between these parts in such a way that in use the adjusting screw and the lower flange will snugly engage respectively with the valve stem and cam at all times.

In the accompanying drawing which illustrates 50 my present invention and forms a part of this specification,

Figure 1 is a sectional side view illustrating the practical application of my invention,

Fig. 2 is a detail side view partly broken away and in section of the lower portion 55 of the tappet,

Fig. 3 is a top plan view thereof,

Fig. 4 is a side view partly broken away and in section of the upper part of the 60 tappet, and

Fig. 5 is a top plan view of the parts shown in Fig. 4.

Referring now to these figures and particularly to Fig. 1 it will be noted that the 65 valve tappet, generally indicated at 10, works through a bearing 11, its lower flanged end 12 depending into the crank case and into engagement with its respective cam 13 of the cam shaft 14. The upper end of 70 the tappet 10 has an axial threaded bore receiving an adjusting nut 15 and is slightly reduced as at 16 to facilitate engagement of a wrench and the like with the lock nut 17 which threads on the screw 15 and in its 75 effective position abuts and tightly engages the upper end of the tappet to lock the adjusting screw in position.

Ordinarily with the parts cold or substantially so the adjusting screw 15 must be 80 slightly spaced from the lower end of the respective valve stem 18 when the valve at the upper end of this stem (not shown) is fully seated under tension of the valve 85 spring 19, in order that when the parts become heated, there will be sufficient room for the valve stem to expand and still permit full, proper and even seating of the valve.

Unless this adjustment is carefully and properly made it is obvious there is considerable 90 danger of free endwise play of the tappet and this is particularly true after slight wear has taken place, which results in a noisy valve action that my invention seeks to overcome.

In carrying out my invention, the tappet is divided into two parts at a point approximately midway between its ends, the lower part 20 carrying flange 12, being cylindrical though entirely closed at its lower end and being adapted to receive in telescoping relation therein a reduced lower extension 21 of the upper part 22 which at its upper end supports the adjusting means as described. The lower end of the extension 21 has an 100 axial bore 23 in which a small coil spring 24 is seated as in Fig. 1 and from which this coil spring partially projects for engage- 105

ment with the lower closed end of the lower part 20. Moreover the lower part 20 has radial oil openings 25 through its wall immediately above its flange 12, through which 5 oil from the crank case finds its way into the bore of the cylindrical part 20, oil also finding its way upwardly on the external surface of this cylindrical part 20 to the space between its upper end and the annular 10 shoulder 26 of the upper part 22 so as to thus form an oil cushion between the abutting portions of the two parts of the tappet both on the upper end of the lower part 20 and the lower end of the extension 21 of the 15 part 22.

It is quite obvious from the foregoing that when the two parts 20 and 21 are pressed lengthwise into closely contacting relation against the compression of spring 24, the tappet presents the same external 20 appearance of the ordinary tappet, is capable of working in the same bearing, and is thus adaptable for use without changing any of the surrounding ordinary parts of 25 the motor in connection with which it is to be used. The spring 24 is of course materially lighter and of less strength than the valve spring 19 so that it presents no impediment to the full closing of the valve under tension of spring 19 although it obviously acts under normal circumstances to shift the two parts of the tappet away from one another in order to maintain the adjusting screw 15 and the flange 12 in even uniform 30 contact respectively with the valve stem 18 and the cam 13.

In adjusting the tappet its parts are pressed tightly together and the adjustment before described as to the adjusting screw 40 15 is effected. Instantly upon release of the tappet its parts expand lengthwise under tension of spring 24 and the uniform engagement above described with the parts between which the tappet is disposed is 45 maintained from this time on. Oil finding its way upwardly upon the external surface of the cylindrical part 20 constantly maintains an oil cushion as previously described between the upper end of this part and the 50 shoulder 26 of the upper part, and simi-

larly oil entering the openings 25 maintains an effective oil cushion at the lower end of the extension 21 so as to prevent noise in use and take up any slight wear as it occurs.

Furthermore the annular space between 55 the upper end of the part 20 and the shoulder 26 of the upper part 22 has the effect of checking upward flow of oil around the tappet through the bearing 11 so as to prevent waste of oil upwardly along the tappet 60 such as frequently occurs in connection with the usual tappet the cylindrical body of which presents a smooth surface from end to end.

I claim:

1. A valve tappet having a body presenting a smooth external surface of one diameter throughout, formed in two parts, the lower part of which is cylindrical and has a lower closed and flanged cam engaging end and the 70 upper part of which has an upper adjusting screw and a reduced depending extension which slidably interfits the hollow lower part and forms a shoulder opposing the upper end of the lower part, and a spring carried between the lower end of said extension and the closed base of the hollow part whereby to place the parts under compression in use, said lower hollow part having an oil intake opening laterally through its wall 75 immediately above its flanged lower end to freely receive oil below the lower end of the extension of the upper part.

2. A valve tappet comprising a lower cylindrical part having a lower closed end and a flange surrounding said end, an upper part having a reduced lower stem slidably interfitting the bore of said lower part and forming an annular shoulder opposing the upper end of the lower part, said upper part having an adjusting screw at its upper end and an axial bore in its lower end, and a spring within the bore bearing against the lower closed end of the lower part, said upper and lower parts being of the same diameter and said lower part having an aperture through its wall opening into its bore above the flange and below the lower end of the upper part as described.

FREDERICK H. BELLMORE.
